UNITED STATES PATENT OFFICE.

DAVID I. GRIFFITHS, OF FROSTBURG, MARYLAND.

DIRECTION-SIGNAL.

1,348,716.

Specification of Letters Patent.

Patented Aug. 3, 1920.

Application filed November 24, 1919. Serial No. 340,355.

To all whom it may concern:

Be it known that I, DAVID I. GRIFFITHS, a citizen of the United States, residing at Frostburg, in the county of Allegany and

5 State of Maryland, have invented new and useful Improvements in Direction-Signals, of which the following is a specification.

The object of my present sole invention is the provision of a simple, easily operated 10 and efficient direction signal, and one that is adapted to be carried in laterally extended position on an automobile body, and in which the parts are so constructed and arranged that when it is necessary to move 15 the signal through a narrow doorway, the signal may be swung parallel to and close against the sides of the body.

To the attainment of the foregoing, the invention consists in the improvement as 20 hereinafter described and definitely claimed.

In the accompanying drawings, hereby made a part hereof:

Figure 1 is a transverse section taken through a portion of an automobile and my 25 novel signal, and showing the latter in working position.

Fig. 2 is a view taken in a plane above the signal, and showing the signal in plan as swung to the idle position.

30 Fig. 3 is a section taken in the plane indicated by the line 3—3, of Fig. 1, and showing the interior construction of the casing of the signal.

Fig. 4 is a section taken in the plane indicated by the line 4—4 of Fig. 1, and showing the driving connection.

Fig. 5 is an enlarged detail view illustrative of the hinged connection between the casing support of the signal and the bracket 40 arm on the automobile body.

Fig. 6 is a detail enlarged view showing the hinged connection of the members of the operating shaft.

Fig. 7 is a plan view showing in regular 45 sequence the eight signs that will be carried on the rotary cylinder that is of octagonal form in cross-section.

Similar numerals of reference designate corresponding parts in all of the views of 50 the drawings.

In furtherance of my invention, the automobile body 1 is provided with a lateral bracket 2, and in the wall of said body is formed a transverse aperture 3. Said aperture 3 is for the passage of the inner section 4 of a sign-operating shaft which also com-

prises an outer section 5 hinged at 6 to and adapted to swing horizontally from the position shown in Fig. 1 to the idle position shown in Fig. 2, and vice versa. At its end 60 remote from the hinged connection 6, the shaft section 5 is provided with a pinion 7.

The bracket 2 is provided with knuckles 8, and to the said knuckles 8 are connected in hinged manner complementary knuckles 9 65 at the end of the straight portion 10 of a support, which comprises, in addition to the straight portion 10, a curvilinear portion 11. The support portion 10 is equipped with a standard 12 that is arranged adjacent to the 70 inner end of the portion 11, as shown.

Superimposed upon and bolted to the support portion 11, is a casing 13 in which are front and rear openings 14 for the display 75 of the signs.

Revolute about its axis in and arranged longitudinally of the casing 13 is a sign-bearing body 15, of octagonal form in cross-section, as appears in Fig. 3. At one end, said body 15 has a trunnion 16 journaled in 80 a bearing 17 carried at the inner side of the outer end of the casing. At its opposite and inner end the revolute body 15 is provided with a trunnion 18 that extends loosely through an opening in the inner end 85 of the casing 13, and is journaled in the standard 12 and is equipped with a spur gear 19, intermeshed with the before-mentioned pinion 7. From this it follows that rotation or turning of the handle 20 on the 90 shaft section 4 will be attended by rotation of the body 15 about its axis.

My invention contemplates the provision of signs at the eight sides of the body 15, and the signs *per se* may be of any desired 95 type without affecting my invention. In the present arrangement I prefer to employ on the body 15 two signs reading—"Right," arranged to be simultaneously displayed through the front and rear openings 14 of 100 the casing 13; two signs—"Left," arranged to be simultaneously displayed through said openings; two signs "Red" to be similarly displayed, and two signs "Seeing U. S. A." for similar double display; the "Red" signs 105 being indicative of danger, and the "Seeing U. S. A." signs indicating that the car is proceeding without intention of stopping or turning. The "Right" and "Left" signs indicate what they import, and it will here 110 be noted that all of the signs of my improvement are displayed to equal advantage to

persons in front as well as persons in rear of the automobile equipped with the signs.

For the purpose of illuminating the signs in the night-time, incandescent lamps 30 are arranged in the casing 13, and wires 31 connected to the filament of said lamp are carried through the inner end portion of 10 the opening in the casing 13 to be electrically connected with a source of electrical energy carried by the automobile.

An important advantage of my invention resides in the considerable lateral extension 15 of the direction signal from the side of the automobile body, and in the provision made for the swinging of the signal to a position close against the side of the automobile body, as when it is necessary to pass the automobile through a narrow doorway.

20 Having described my invention, what I claim and desire to secure by Letters-Patent, is:

The combination in a direction signal of the side wall of an automobile body, said

wall having a transverse opening therein, a bracket on the outer side of said wall below said opening and having a knuckle, a support having a knuckle connected in hinged manner to the knuckle of the bracket, a casing superimposed upon and connected to said support and having front and rear 25 openings, a rotatable sign-bearing body journaled in the casing and having a trunnion extended through the inner end of the casing and journaled in the support and equipped with a spur gear, a shaft section 30 extended through the opening in the wall of the automobile body, and a shaft section connected by a hinge with the first-named shaft section and having a pinion intermeshed with said spur gear, the pintle of 35 said hinge being disposed in vertical alignment with the pintle connecting said knuckles.

In testimony whereof I affix my signature.

DAVID I. GRIFFITHS.
